CLAIM

The ornamental design for a fluorescent trouble light, as shown and described.

DESCRIPTION

FIG. 1 is a front elevational view of the fluorescent trouble light showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

The electric cord is broken away to indicate indeterminate length.
